UNITED STATES PATENT OFFICE

BARTON R. SHOVER, OF PITTSBURGH, PENNSYLVANIA

APPARATUS FOR ROLLING STRIP METAL

Application filed July 8, 1928. Serial No. 120,765.

In the rolling of long steel or other metal strip which is not reheated during the rolling operation, it is impossible because of heat losses to reduce the metal to the thin gages 5 frequently desired, and for the same reason it is difficult to maintain uniformity of the heavier gages to which the metal may be reduced. Also, the loss of heat results in such hardening of the strip in the final roll pass or 10 passes that considerable annealing is necessary before the metal may be used or further worked. The heat losses of the strip are due, first, to conduction by its contact with the cool metal of guides, transfer tables, troughs, and 15 such other instrumentalities as are used to convey or direct the strip from one to another of successive roll passes, and secondly, to radiation of heat to the atmosphere from the exposed strip as it moves from one roll pass to another. Aside from these and other prejudicial effects incident to heat losses, the large 20 exposure of the heated strip results in material oxidation of its surface with undesirable consequences well understood by those skilled in the art. Furthermore, the provision 25 of the necessary apparatus now used for conveying strip between roll passes frequently entails large expense. Its original cost is heavy, it requires continual upkeep, it frequently 30 occupies a large amount of valuable mill space, and the power required for rolling is high because of the low finishing temperature.

The object of this invention is to provide a 35 simple and effective apparatus for rolling strip, whereby dissipation of heat from the strip is largely eliminated so that the strip may be rolled to more uniform and to lighter gages, and whereby oxidation of the strip may be materially reduced, and the cost of production of the strip substantially lowered.

The characteristic feature of this invention consists in reeling hot rolled strip as it emerges from a roll pass. In doing this the 45 sides of the strip are quickly brought into direct contact with each other so that the heat of the strip is not dissipated either by conduction or radiation, and so that the sides of the strip are protected against oxidation. 50 The strip with its heat thus conserved and

so protected against oxidation, is then transferred to a position for feeding it directly from the reel into a second roll pass. This reeling and unreeling of the strip may be, and according to this invention preferably is, 55 repeated through a succession of roll passes until the strip is reduced to the desired gage. However, several reels of hot strip may be so placed that the strips may be simultaneously unreeled and fed into a single roll pass 60 in stacked arrangement.

In the preferred practice of the invention a blank is rough rolled in any suitable or desired arrangement of rolls until it is reduced to such thickness that it may be reeled as it 65 emerges from the rolls. Adjacent to the discharge side of the pass from which the strip is to be reeled there is an automatic motor-driven reel for catching and tightly reeling it. The reel may, if desired, be suitably 70 heated not only to prevent dissipation of heat by conduction from the strip into the reel, but also to compensate for the small amount of heat that may be previously lost. The reel is preferably mounted for convenient transfer 75 to a position for feeding the strip directly from the reel into the succeeding roll pass. While various forms of transfer apparatus may be provided, by way of example the successive pairs of rolls may be arranged substantially 80 end to end and the reel mounted upon a turret or turn-table which may be rotated to move the reel from its strip-receiving to its strip-discharging position. The turret may be provided with two reels diametrically 85 arranged so that one strip may be received from the discharge side of a pair of rolls and another may be fed into the entering side of a succeeding pair of rolls. This procedure and arrangement of apparatus may be repeated between each successive pass.

This generally described embodiment of the invention is illustrated in the accompanying drawing, which is a diagrammatic plan view of roughing and finishing mills, 95 and of reels arranged between adjacent roll passes of the finishing mill.

As shown in the drawing, the roughing of blanks is effected in three stands of rolls 1, 2 and 3, the rolls 1 being driven by a motor 4, 10

and the rolls 2 and 3 by a motor 5. The path of a blank in passing through these roughing rolls is that generally indicated by the dot and dash line 6. However, it will be understood that the roughing of blanks may be effected in any desired manner and on any suitably arranged roughing rolls.

The drawing shows a finishing mill consisting of five stands or pairs of rolls 7, 8, 9, 10 and 11 arranged end to end, the rolls 7, 8 and 9 being driven by a motor 12 and the rolls 10 and 11 by a motor 13. Between the pairs of rolls 8 and 9, and on the discharge side of the former and the entering side of the latter, there is a reel support in the form of a rotatable turret 14 on which there are mounted two automatic reelers 15 and 16 which may be driven by motors 17 and 18, respectively. Similarly, reels 19 and 20 are mounted on a rotatable turret 21 arranged between the pairs of rolls 9 and 10, the reel 19 being shown in a position to receive a strip from rolls 8, and the reel 20 in a position from which a strip may be fed directly from it into rolls 9. This general arrangement is shown as being repeated between each of the succeeding pairs of rolls in the finishing mill.

As a strip emerges from the first pair of rolls 7 it is caught and automatically reeled upon reel 15. Turret 14 is then turned to immediately place reel 15 in front of the second pair of rolls 8. A workman may engage the end of the strip by a pair of tongs and place it in the bite of rolls 8, or suitable mechanism may be provided for this purpose. While the strip is being withdrawn from reel 15 by rolls 8, a second strip may be coiled upon reel 16 when in the position opposite to that indicated in the drawing. At the discharge side of rolls 8 the strip is again automatically caught and coiled upon reel 19, and from this on the procedure is repeated until the strip is reduced to its desired gage.

In the practice of this invention very little heat is lost from the strip as it is passed through successive passes of the finishing mill. Because of this, strips are reduced to much thinner gages than heretofore possible, and, regardless of the gage to which it may be desired to reduce it, the thickness of each strip remains substantially uniform due to its being rolled at a relatively high temperature, and to the fact that each pass rolls the strip in the opposite, or reverse direction. Furthermore, oxidation of the surfaces of the strip is very substantially reduced, its sides being exposed to the atmosphere only while it is passing from one reel to another on opposite sides of roll passes. Because of this conservation of heat, less rolling power is required. In addition to the advantages which have been pointed out, the apparatus essential for the practice of the invention is inexpensive and occupies a much smaller space

than the apparatus customarily used for rolling strip. These and other advantages will be readily apparent to those skilled in the art.

The word "strip" as used throughout this specification and in the claims is not limited to metal of any maximum width. It is intended to include narrow strips as well as strips of a width which are customarily known as sheets, as for example strips of widths of sheet metal used in the manufacture of tin plate. Furthermore, while the invention applies primarily to the rolling of strip steel, it is also advantageous in the rolling of light sections, such as rods, small squares, hoops, and the like.

According to the provisions of the patent statutes I have described the principle and mode of operation of my invention, and have diagrammatically illustrated the preferred construction and arrangement of apparatus. However, I desire to have it understood that, within the scope of the appended claims, the invention may be practiced otherwise than specifically described and on apparatus other than that particularly illustrated.

I claim as my invention:

1. A hot strip rolling mill, comprising two roll passes, a movable support provided with a pair of strip reels, and means for reeling upon one reel hot strip emerging from one roll pass while hot strip is simultaneously fed directly from the other reel to the other roll pass.

2. A hot strip rolling mill, comprising two roll passes, a rotatable turret provided with strip reels, and means for reeling upon one reel hot strip emerging from one roll pass while hot strip is fed directly from the other reel to the other roll pass.

In testimony whereof, I sign my name.
BARTON R. SHOVER.
